UNITED STATES PATENT OFFICE

HARRIET LYONS REDMOND, OF NEEDHAM, MASSACHUSETTS, ASSIGNOR TO THE WILLIAM CARTER COMPANY, OF NEEDHAM HEIGHTS, MASSACHUSETTS, A CORPORATION OF MASSACHUSETTS

WOMAN'S UNDERGARMENT

Application filed January 20, 1930. Serial No. 421,902.

My invention relates to women's undergarments, and, more particularly, aims to provide a soft, pliant undergarment which is adapted to serve both as a shirt or vest and as a corset, corselet, or sustaining garment, to confine and mould the figure in a manner heretofore obtained only with a plurality of heavier bulkier garments, or by a garment or garments of relatively firm, 10 non-yielding fabric.

My invention further relates to and embodies a shaped, sustaining soft, pliant undergarment so constructed both in point of form or shape, and in nature of fabric employed that the desired figure-moulding characteristics primarily accomplished by the form or shape and construction, are further accentuated and enhanced by the constant presence or existence during wear of 15 a downward vertical pull produced or delivered between the top and bottom parts of the garment. The means by which this pull is produced is also provided, in accordance with my invention, and obviously can be 20 widely varied within the scope thereof.

In the drawings illustrating one embodiment of the invention, by way of example,—

Fig. 1 shows the garment as laid out flat-wise;

Fig. 2 is a plan of a fabric blank which may be used in forming the garment front;

Figs. 3 and 4, on a smaller scale, show the garment in position as worn, Fig. 3 being a three-quarter front view and Fig. 35 4 a right side view with the left leg positioned slightly to the rear of the right leg;

Fig. 5 is a sectional detailed view on the line 5—5 of Fig. 1;

Fig. 6 is a view similar to Fig. 2 of a 40 slightly modified but equally effective form of fabric blank; and

Fig. 7 is a sectional detail view of the preferred elastic stitching at the seams.

The garment as a whole comprises a front 45 portion 6 and a rear portion or back 7 suitably secured together preferably by elastic stitching, one type of which is shown in Fig. 7 at 7^a, to form a fashioned tubular trunk covering, preferably (but not necessarily) 50 with no openings at the sides but adapted

to be slipped on over the wearer's head. Various materials or combinations of materials may be employed in forming the garment, desirably of a soft, pliant character and light in weight as compared, for example, with elastic webbing made of woven material and the like such as used in corsets, girdles and similar garments, the desired fabric having but limited or markedly restrained elasticity. Preferably I employ, 55 and have illustrated, a knitted fabric, herein disposed with the knitting wales 8 extending vertically, and being so knitted as to have but slight elasticity even in the direction cross-wise of the wales, as contrasted, 60 for example, with rib-knitted fabrics and others commonly used in underwear. I may employ a flat-knit fabric. In some cases I may employ rib-knitted fabric provided however the feature of constant vertical 65 pull during wear is preserved. It is to be noted that irrespective of the natural characteristics of the particular fibres or yarns used, the construction of the fabric, whether flat knitted, circular knitted or otherwise, 70 is of such a nature as to permit a certain amount of lateral contraction when expanded lengthwise. The knitted looped construction illustrated is preferred but other suitable constructions might be used, as for 75 example rib knitting under certain conditions.

A fabric blank from which the front of the garment may be formed is shown in Fig. 2. As there illustrated, it is an integral piece of fabric, of the character above referred to, comprising a main or body portion 9 and an upper portion or bandeau section 10. The main portion 9 is fashioned at its sides to provide the set-in waist-confining portion 11 which leads downwardly into the portion 12 for moulding and restraining the lower abdomen and the hips. The lower edge of the garment is desirably formed substantially in the manner illustrated to provide tab-like extensions 13, 13, 80 one at each side of the vertical centre line and connected by the arcuate central portion 14. As shown in Fig. 6, the upper 85

portion or bandeau section may be formed as a separate piece 10^a.

The upper or bandeau portion 10 of the garment front, in the form as in Fig. 2, is somewhat wider than the main portion 9. The blank, in this embodiment of the invention, is slotted inwardly from its opposite side edges, as indicated at 15, 15, along generally horizontal but arcuate lines defining the juncture of the main portion 9 and the bandeau section 10 but in certain cases may be made by straight cuts. These slit formations 15 approach each other so as preferably to leave a relatively narrow uncut area 16 between them. The bandeau section 10 thus comprises two opposed, laterally extending bust portions 17, 17. From each of these I cut out one or more gores, leaving substantially vertical cut-out formations to assist in conforming the garment to the bust. In the form illustrated two such formations are let into each bust portion 17, one extending upwardly from the lower edge thereof about mid-length of the slit formation 15, as indicated at 18, and the other, as indicated at 19, let in from the upper edge approximately vertically opposite the one first mentioned. It is to be understood, however, that the desired effect may be produced otherwise than by gores and that any suitable means for accomplishing this purpose is within the spirit and scope of my invention. In fact, the formation of the bust section can be accomplished in so many different ways, that I wish it clearly to be understood that I have disclosed but a single illustrative embodiment of my invention, to which, however, I am in nowise limited.

In forming up the blank the edges of the respective cut-out formations 18, 18 and 19, 19 are brought together and secured by darts, or other shaping means, as seen at 20, 20 and 21, 21, Figs. 1, 3 and 4. The material of the bandeau section 10 is thus brought in laterally to correspond to the width of the upper part of the main portion 9, forming two cupped or pocket-like members, also indicated by the numerals 17 in Figs. 1, 3 and 4, the lower edges of which are seamed to the main portion 9, as at 22, 22, Fig. 1.

The foregoing described construction provides two cupped or pocket-like members and the fabric of which the garment is composed and which receives the downward pull at the lower end (as hereinafter more fully referred to), cooperates with said cupped or pocket-like members by accentuating or emphasizing the cupping action in that the downward pull insures the full effectiveness of the described construction by which cupped or pocket-like members are provided. The same is also accentuated by

the upward pull or pull against the shoulder straps.

The lower edges and the inner side edges of these two members of the bandeau section are further defined and given additional supporting ability by means of fabric strips, preferably of the same material as the garment as a whole and stitched in position over-lying the seams 22, 22. They may be flattened knitted tubes or fabric strips having their side edges in-folded, as seen in Fig. 5, two lines of stitching being employed to retain the strip in that form and to secure it in position. One of these strips, herein the strip 23 at the right, extends from the side edge of the garment front in a curved manner across one-half of the bandeau section and thence vertically upward to the garment top. The other and corresponding strip 23a terminates at its point of meeting with the strip 23. It is clearly to be understood that I have here described and illustrated one only of many ways of accomplishing this desired object of my invention and that I am not limited to that disclosed. It will be understood from the foregoing description that I have provided in a garment of the character described, at the front thereof, transversely extending reinforcing means at the under-bust part of the bandeau portion to which means the downward pull is transmitted and cooperating with said shoulder engaging supporting means to assist the bust-molding and uplifting. Obviously the invention is not limited to the construction herein shown for this purpose.

The back 7 of the garment as illustrated is likewise formed of a single piece of material of the character referred to. Its lower edge also desirably is scalloped to provide the tab-like portions 25, 25, Figs. 1 and 4, preferably spaced at somewhat less distance than the similar tab-like extensions 13, 13 at the garment front. The garment back likewise is fashioned in conformity with the front 6 to provide waist and hip confining portions cooperating with those of the garment front to suppress and mould the entire figure.

The garment so formed, in the nature of combined vest, corset and brassière or bandeau, is closely form-fitting, as seen in Figs. 3 and 4. It provides extreme trimness but without rigidity, holding the figure without loss of suppleness to clear-cut firm lines throughout but especially at the waist, the hips and the bust, but at the latter point acting to uplift and round the bust while supporting it, rather than merely to flatten it. The described form-fitting shape, while highly desirable in itself as co-operating toward the accomplishment of my invention, is one only of several features, all of which coact together in effecting the entire purpose of my invention. Particularly does the dis-

closed shape co-operate with the constant presence during wear of a downward vertical pull, which latter feature is of primary importance.

5 In order to increase the moulding effect of the garment still further and to aid in the even distribution of the desired lengthwise pull, I desirably but not necessarily employ a plurality of vertical supporting and confining elements suitably disposed about the garment. In the present instance two such stay-like but pliant elements 26, 26 are located upon the garment front, extending upwardly along slightly convergent lines from the tab-like extensions 13, 13 to 10 or substantially to the bandeau section, meeting the latter substantially centrally of the two bust portions. These elements may be termed self-supports, being preferably 15 of self-material with respect to the garment as a whole, that is, they are desirably but not necessarily formed of the same or substantially similar fabric as that of the body of the garment, illustrated as a fine-mesh-knitted fabric. These elements, similarly 20 as the members 23, 23^a, may be formed as flattened tubes or substantial tubes, comprising strips having their side edges in-turned and so secured, together with the 25 strips as a whole, by parallel lines of stitching as clearly shown in section in Fig. 7. Similar self-supports or confiners 27, 27 are shown at the back of the garment extending from the rear tab-like extensions 25, 25 upwardly to or approximately to the garment 30 top. Desirably also similar confining and supporting devices are placed at the garment sides, as at 28, 28, these overlying the seam lines which join the sides of the garment 35 front and back portions 6 and 7. I desire it clearly to be understood that the so-called "stay-like elements" may be applied in a great many ways and at many different angles, and in certain cases may be wholly 40 omitted or omitted in part.

In the illustrative form of the invention, provision is made for the attachment of garters at the lower portion of the garment. Herein for the purpose I have illustrated

45 a series of button-holes or like formations 29, 29, 29, 29 at the lower extremities of the several tab-like extensions 13, 13 and 25, 25, see particularly Fig. 1, extending through the adjacent portions of the vertical supporting elements 26, 26 and 27, 27 50 and adapted to receive buttons or other attaching devices for the garters 30, such as the key-like devices illustrated at 31, 31, Figs. 3 and 4. Similar garter-attaching 55 provision may be made at the lower portions of the side confiners 28, 28; see Figs. 3 and 4. Thus arrangement is made for attaching three garters for each stocking, at front, back and sides, respectively, although a different number may be provided

for if desired. Desirably one or more additional series of button-holes or other attaching means are supplied, at a different height on the vertical members 26, 27 or 28, affording adjustability in the point of garter support. It will be understood that other forms of garter attachment may be employed, depending upon the type of garter, as, for example, a reverse construction, the button-holes being in the garters and the co-operating securing devices such as buttons, studs or the like, being upon the garment. Garter-means constitute the preferred way of insuring the lengthwise pull on the garment to which I have repeatedly referred as a primary feature of my invention, while at the same time producing the desired lateral contraction and keeping the garment continually snug-fitting, etc.

80 Suitable shoulder straps 33 may be provided at the garment top, desirably having their respective ends secured in substantial alignment with the back supporting elements 27, 27 and the similar front elements 26, 26. It will be noted that these vertical elements 85 thus not only serve further to confine and firmly mould the diaphragm, waist and hip portions, but also act to distribute the garter strain over substantially the entire garment, and to carry the major portion thereof directly to the garment-supporting shoulder straps. The shoulder straps, of whatever type employed need not be permanently secured to the garment, but may be rendered 90 detachable in any suitable manner.

95 The bottom edge of the fabric may be finished in any suitable manner, as by a folding over and securing of the lower edge of the fabric itself, or by the application to the edge of a similar fabric, or elastic inserts or any suitable binding. In the present instance I have represented a tape-like binder or edge lining at its inner face at 34, Fig. 1, which is somewhat or sufficiently elastic. The binding may be and herein is a bias 100 binding. A similar edging 35 may be supplied for the garment top, further increasing the moulding and suppressing effect of the entire garment.

105 It will be observed that certain features of the invention are also applicable to circular-knit garments, also that the front and rear sections might be formed from a different number of fabric pieces than as herein illustrated, the seam lines being conveniently located in the line of any one or more of the vertical self-supports, or even elsewhere.

110 From the foregoing description taken in connection with the drawings it will be understood that I have provided a foundation garment of firm pliant material giving roundness and uplift to the bust and suppression or moulding to the remainder of the figure, insuring to it definite trim lines 115 120 125 130

but without loss of suppleness and without resort to bulky materials, objectionable side snaps or other fasteners, or other objectionable features, and that a continually snug figure-moulding fit is insured, irrespective of the position the wearer normally assumes, due to the give and take of the fabric. One of the numerous additional advantages of the garment of my invention lies in the ease with which it may be cleansed, the garters being readily detachable, whereupon the garment may be washed and dried as easily and quickly as the usual silk vest.

I desire it to be understood that I have illustrated one embodiment of the invention and have specifically described the same, but that the invention may be embodied in garments otherwise shaped and otherwise constructed than that shown, provided the features of the invention be preserved. The garment illustrated and described is adapted to the present style of dress, but it is clearly to be understood that the garment of my invention may be adapted to other styles of dress without departure from my invention, as, for example, by cutting down the back, or in other ways not necessary to enumerate specifically.

While I have specifically described a desirable construction of bandeau section, it is to be understood that the invention is not restricted thereto. Square or substantially rectangular bandeau sections or parts may be employed and the bandeau part or section may itself be made of a plurality of pieces provided the purpose and principle of the invention are retained. The garment may be made without stays and is so illustrated.

Furthermore, secondary additions may be applied to the garment, such, for example, as skirts, bloomers, pants or the like. Therefore, the invention is not limited to a garment of the length indicated in the drawings.

Furthermore, the garment may be further reinforced either by additional self-material or by other material, as by elastic suitably placed, without altering the basic characteristics of the invention.

Having thus described one illustrative embodiment of the invention, it is to be understood that although specific terms are employed, they are used in a generic and descriptive sense and not for purposes of limitation, the scope of the invention being set forth in the following claims.

Claims:

1. A fabric blank for the front portion of a woman's undergarment comprising a main section having side edges fashioned to define the waist and hip areas and a bottom edge having tab-like extensions at opposite sides of its vertical center line, the upper section of the blank above said main section being wider than its immediately lower por-

tion, the blank being slitted inwardly from its sides between said two sections, vertical cut-outs in the upper section, at opposite sides of the vertical center line of the blank, one extending upwardly from the upper edge of each of said slitted formations, and others extending downwardly from the top edge of the blank, in substantial opposition to those first mentioned.

2. A fabric blank for the front portion of a woman's undergarment comprising a main or body section and a bandeau section having a width greater than the adjoining upper part of the main section, opposed slit formations extending in from the sides of the blank between said two sections, and one or more substantially vertical wedge-shaped cut-out formations in the fabric bandeau section above each of said slit formations.

3. An entire-body-molding knitted foundation undergarment for women, to be worn next to the body and to provide a uniformly distributed molding and form-defining effect from and including the bust to and including the thighs; said garment comprising a body portion devoid of front opening and of materially less diameter at the waist region than at the thigh and bust regions, and being closely and circumferentially uniformly knitted throughout so that it is inherently and evenly of markedly restrained lateral expansibility, thus providing an equal molding and suppressing effect for the entire body below the bust, and a formed shoulder-supported bandeau portion extending transversely across the front top of the body portion, of a fabric of similar markedly restrained expansibility as the latter, and including pocket-like sections roundly to support the bust, said garment having at the base of the bandeau portion transversely extending strip-like reinforcements which receive the downward pull of the garment transmitted thereto from the lower garment end, and said garment having provisions whereby, during wear, it can be subjected to a constant downward pull, as by the attachment of stockings thereto, which cooperates with said structure and shape of the garment to increase its said molding and suppressing effect.

4. A knitted foundation garment for women, for wear next the flesh and to serve as shirt or vest, garter-supporting corset and brassière; comprising front and back portions, each formed wholly of a soft, pliant fabric, so tightly knitted as to give it markedly restrained expansibility even in the cross-wale direction, each portion having a decreasing width from approximately its bottom to about mid-height and thereabove increasing in width, said portions united along their vertical edges to form a closed body-covering, shaped so as uniformly to

- suppress and mold the entire body of the wearer from and including the thighs to the bust, a bust-uplifting and rounding brassière section at the top of the garment portion, constructed of a fabric material of similar markedly restrained expansibility and including two cupped bust portions for roundingly supporting the bust rather than merely flattening it, a plurality of narrow vertical members of knitted fabric secured flatwise against said body-covering, two of said members located at the garment front respectively in line with the central areas of the two portions of the brassière section and terminating at the lower edge thereof, shoulder straps having their front ends secured to the upper edge of the brassière element in substantial line with said front vertical members, said bust portions of the brassière section having marginal reinforcements acting to transmit the main vertical garment strain around said portions and to said shoulder straps rather than directly through or across said portions, thereby to contribute to the roundingly supporting effect of the brassière section, the said construction of the garment as a whole being such, both in point of said form or shape and of said fabric that said bust-uplifting and body-molding action will be attenuated during wear by a vertical downward pull as by the attachment of garters and stockings at the garment bottom.
5. A knitted garment for women for wear next the flesh and to serve as shirt or vest, garter-supporting corset and bust-rounding and uplifting brassière or bandeau; said garment being permanently closed at the front and providing a uniformly distributed, molding and form-defining effect from and including the bust to and including the upper thigh portions, and for that purpose being of soft, pliant fabric that is of markedly restrained expansibility lengthwise and transversely; said garment from and including its lower part to approximately the bust portion being so closely and circumferentially uniformly knitted that it is inherently and evenly of markedly restrained lateral expansibility, thus providing an equal molding and suppressing effect for the entire body below the bust; said bust-uplifting brassière or bandeau portion extending transversely across and constituting the garment top front, said brassière or bandeau portion including two bust-uplifting fabric portions having substantially radial shaping formations extending in from their margins to give them a cupped or pocket-like form, said brassière or bandeau portion and the adjacent part of the main section of the garment front having transversely disposed reenforcing means to receive downward pull of the garment transmitted thereto from the lower garment end.
6. A knitted foundation garment for women for wear next the flesh and to serve as shirt or vest, garter-supporting corset and bust-rounding and uplifting brassière or bandeau; said garment being permanently closed at the front and providing a uniformly distributed, molding and form-defining effect from and including the bust to and including the upper thigh portions, and for that purpose being of soft, pliant fabric that is of markedly restrained expansibility lengthwise and transversely; said garment from and including its lower part to approximately the bust portion being so closely and circumferentially uniformly knitted that it is inherently and evenly of markedly restrained lateral expansibility, thus providing an equal molding and suppressing effect for the entire body below the bust; said bust-uplifting brassière or bandeau portion extending transversely across and constituting the garment top front, being composed of a fabric of similar markedly restrained elasticity, and being provided with shoulder-engaging supporting means; said garment having means at its lower portion, whereby, during wear, it can be subjected to a constant downward pull, said means cooperating with the fabric structure of the garment to increase its molding and suppressing effect; and said garment including front transversely extending reenforcing means at the under-bust part of the bandeau portion to which means the said downward pull is transmitted and cooperating with said shoulder-engaging supporting means to assist said bust molding and uplifting.
- In testimony whereof, I have signed my name to this specification.
